UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

MACHINE FOR ASSEMBLING MATCH-BOOKS, &c.

1,217,991.

Specification of Letters Patent.

Patented Mar. 6, 1917.

Application filed May 5, 1916. Serial No. 95,713.

To all whom it may concern:

Be it known that I, MICHAEL PARIDON, a citizen of the United States, and resident of Barberton, in the county of Summit and State of Ohio, have invented certain new and useful Improvements in Machines for Assembling Match-Books, &c., of which the following is a specification.

This invention relates to that class of machines whereby book-matches and similarly-shaped articles are assembled side by side with the corresponding ends of the contiguous articles in opposite relation to each other. The invention may be described as a modification of the positioning and assembling mechanism set out in Letters Patent of the United States No. 1,132,268, dated March 16, 1915, which mechanism is therein illustrated as associated with a match-book making machine of the character described in Patent No. 1,042,472, dated October 29, 1912. In the machine of the latter patent match-books, wedge-like or tapering in form, (owing to the match heads of the covered cards or splints) are discharged from an intermittently rotatable turret element in succeeding pairs with the larger ends of the books rearward; and in the machine of the first-mentioned patent the said positioning member is mounted and operated in such relation to the turret element as to receive the books as rapidly as they are thus discharged and to position them for delivery with their larger ends alternately reversed. An object of the invention is to provide a simple and efficient construction and arrangement of mechanism whereby the articles discharged from the positioning member are directly deposited side by side in a receptacle and therein assembled in a column or columns, said receptacle being of such character that predetermined quantities of the articles can be readily removed therefrom for convenience of packing by hand. Another object is the provision of mechanism whereby the efficient operation of the positioning and assembling mechanism in harmony with the operation of the book-match machine is accomplished. With these and other objects in view my invention comprises various features of construction and combinations of parts which will be hereinafter described and claimed.

In the drawings—

Figure 1 is an end elevation of a match-book assembling machine embodying my invention, showing its relation to and connection with a match-book machine, whereof only so much is shown as is necessary to illustrate the invention. 55

Fig. 2 is a plan, partly in section, (as on the line 2—2, Fig. 1) of the book-assembling machine, and the operative connections between its moving parts and a shaft of the match-book machine. 60

Fig. 3 is a longitudinal section, partly in elevation, of the receiving end of the receptacle, and adjuncts, as on the line 3—3 of Fig. 2; the parts being shown in the relative positions which they occupy when the vertical book-discharging rods are at the limit of their down stroke in the book-positioning member. 70

Fig. 4 is a plan of the oscillatory book-positioning member. 75

Fig. 5 is a transverse section thereof, as on the line 5—5 of Fig. 4.

Fig. 6 is a partial plan of the receiving end of the chute, and the plunger head therefor. 80

Fig. 7 is an end view of Fig. 6.

Referring to the match-book machine, which, in the present instance, constitutes the source of book-supply for the assembling mechanism, 10 designates an intermittently-rotatable pocketed wheel, or turret, from which the books (a) are discharged in pairs, larger or headed ends rearward, upon a yielding supporting plate 11 by the action of the ejecting arms 12 of a reciprocating frame 13. 85

14 designates reciprocative fingers by means of which the free ends of the cover flaps of the books are tucked under the stapled end folds of the covers. When the 95 tucking operation has been completed and the fingers leave the finished books, the latter are simultaneously pushed rearwardly, abreast, by the next succeeding pair of books, and so on. 100

15 designates an oscillatory book-positioning member comprising a cylindrical body having two pairs of intersecting passages or chambers 16 extending diametrically therethrough at right angles to each other. This 105 body is carried by axial studs 17 having

their bearings in a suitable bracket structure 18 located adjacent the free end of the supporting plate 11, whereby when the body is oscillated the pairs of passages thereof are successively positioned in a horizontal plane to receive the articles pushed from the plate. In one oscillatory stroke of the body the articles contained in one pair of passages are carried downward from a horizontal to a vertical position so that the narrow ends of the articles point downward, and in the next stroke the articles contained in the other pair of passages are carried upward from a horizontal to a vertical position so that the narrow ends of the latter articles point up. The articles thus positioned in opposite end-wise relation to each other by the oscillatory body are discharged therefrom into the directly underlying receiving end of a suitable receptacle 19 by vertical plunger rods 20 which are arranged in spaced relation to each other and are movable into and from the vertically-positioned passages of the body 15 during each dwell of the latter. The books thus delivered to the receptacle are progressively advanced therealong in two parallel columns by means of a reciprocative head, as 21, carried by a horizontal plunger 22.

Projecting from a bracket 23, adjacent a positively driven shaft 24 of the match-book machine, is a stud 25 on which are mounted to rotate as a unit a gear wheel 27 and a cam 28; said gear wheel meshing with and being driven by a gear wheel 26 on the shaft 24. Bearing against the cam is a roller 29 on an inclined reciprocative rod 30 which is pivoted at its upper end to a crank arm 31 on one of the axial studs of the oscillatory body. The lower end of the rod is guided in a suitably-disposed diametrical opening in the stud 25, and the roller is maintained yieldingly against the periphery of the cam by the action of a retracting spring 32 which is secured at its respective ends to said stud and the upper pivoted portion of the rod. The contour and speed of rotation of the cam are such as to effect the longitudinal reciprocation of the rod, and insure the timely oscillation of said body through an arc of ninety degrees; said rod being positively raised by the cam and retracted by the action of the spring. (See Figs. 1 and 2.)

On the shaft 24 is a cam 33 against which bears a roller 34 on one arm of a lever 35 which is pivoted on brackets 36 secured to the frame of the match-book machine. The other arm of the lever is pivoted to the lower end of a vertical plunger rod 37 which is guided in the bracket structure 18. The upper end of the rod 37 bears a head 38 from which depends the book-ejecting rods 20.

The roller 34 of lever 35 is maintained

normally against the periphery of the cam 33 by the action of a retracting spring 35' which is secured at its respective ends to the roller bearing arm of the lever and to the frame of the book-match machine; and the contour and speed of rotation of the cam are such as to effect and permit the timely actuation of the lever and the plunger connections when the oscillatory body is at rest. By this construction it will be seen that the ejecting rods 20 are positively raised by the cam, but in their descent are caused to bear upon the opposing books with a yielding force. Hence, in the event of a book or books becoming jammed between the oscillatory body and the receptacle the forcible action of the rods on the opposing books will be prevented. This yielding feature of the ejecting rods permits the employment of simple and efficient means whereby predetermined books, when they are deposited in the receptacle, may be caused to project above the others and thus afford "counters" to facilitate the removal of predetermined quantities of books from the receptacle. The counting mechanism will form the subject of a separate application for patent.

The receptacle 19 comprises a trough or chute into which the pairs of match-books are successively ejected from the oscillatory body. This trough or chute is preferably an integral part of the bracket structure 18, and the body of the chute is provided with a depending bracket portion 39 which is mounted upon a suitable supporting frame 100 40. The trough or chute is also preferably divided, by means of a longitudinally extending partition 41, into two compartments for the reception and guidance of the two columns of match-books; and it is also preferably curved or inclined upwardly and outwardly from its receiving portion to a position where the books can be conveniently reached and removed by an attendant. The side walls of the chute, at its upper end, are cut away, as at 42, to permit ready access to the columns of books to facilitate their removal.

The plunger head 21 by means of which the successive pairs of books delivered to the chute are advanced along the latter, preferably comprises a body having formed on its inner side two spaced projections α for acting against the opposing books. The portion of this side above the projections is 120 curved (as at γ) correspondingly with the adjacent portion of the book-positioning member so as to serve as a guard for the outer narrow ends of the books as they are being carried downward by said member. 125 The body is provided with upstanding side extensions 21', which serve to guide the books from said plate 11 into the chambers of the positioning-member.

The head 21 is secured to the up-turned 130

ends of a pair of horizontal plunger rods 22, which are guided horizontally in perforations in the depending bracket portion 39 of the chute. These rods are united by a 5 cross-head 43 which is pivotally connected by means of a rod 44 with a crank 45 on a shaft 46 having its bearings in the brackets 36 on the frame of the book-match machine. The shaft 46 bears a pinion 48 10 which meshes with and is driven by the gear wheel 27 on the stud 25 above referred to. The gearing and crank connections are so proportioned and correlated that the plunger 22 is reciprocated after the discharge 15 of each pair of match-books from the oscillatory positioning member.

The rod 44 preferably comprises two sections relatively movable longitudinally of each other and having a yielding connection 20 therebetween. In the present instance the adjacent ends of the sections are slidingly incased by a sleeve 47 having suitably-disposed longitudinal slots 49 therein through which extend from the respective sections 25 studs 50' which take against the opposing ends of a spring 50 encircling the sleeve. This construction affords a yielding connection between the sections of the rod, whereby in the event of a book or books 30 becoming clogged between the plunger and the member 15, the spring will be compressed and the forcible action of the plunger head on the opposing book or books will be prevented; thereby obviating the otherwise liability of bending the rod or stripping 35 the gears or choking the chute.

The side walls of the chute, at the receiving end thereof, are provided with spring clips 51 having beveled inwardly-projecting portions 52 which serve as yielding 40 abutments for the opposing edges of the books as they are deposited in the chute by the oscillatory member, thereby preventing accidental displacement of the books. (See 45 Fig. 6.)

By the above described construction it will be seen that the oscillating positioning member and the respective plungers are operatively connected with a positively driven 50 shaft of the match-book machine in a manner to effect and insure the harmonious operation of the two machines; and that the match-books are directly discharged in an orderly manner from the positioning member 55 to the chute and are therein arranged in two columns and advanced to a position where predetermined quantities of the books can be conveniently grasped and removed from the columns by an operator.

60 It is to be understood that my invention is not limited to the particular constructions herein shown and described, as the mechanism may be variously modified without departing from the spirit of the invention.

I claim—

1. In an assembling machine, the combination of an article-positioning member having intersecting chambers extending therethrough, means for oscillating said member whereby its chambers are successively shifted to horizontal and vertical planes, means for delivering articles to the successive chambers when they are in a horizontal plane, means for ejecting the articles from said chambers successively when they are in a vertical plane, a receptacle having a portion located beneath and adjacent to said member, whereby the articles are directly deposited side by side in said receptacle as they leave said member, and means for progressively advancing along said receptacle the articles delivered thereto. 75

2. In an assembling machine, the combination of an article-positioning member comprising a rotary body having intersecting chambers extending therethrough, a crank member on said body, a positively-driven shaft, a cam thereon, a rod connected with said crank member and operatively engaged with the cam, whereby said body is oscillated to shift its chambers successively to horizontal and vertical planes, means for delivering articles to the successive chambers of said body when they are in a horizontal plane, means for ejecting the articles from said chambers successively when they are in a vertical plane, a receptacle having a portion located directly beneath and adjacent to said member to receive the articles side by side as they are successively ejected, and means for progressively advancing along said receptacle the articles delivered thereto. 95

3. In an assembling machine, the combination of an article-positioning member having intersecting chambers extending therethrough, means for oscillating said member to shift its chambers successively to horizontal and vertical planes, means for delivering articles to the successive chambers when they are in a horizontal plane, means for ejecting the articles from said chambers successively when they are in a vertical plane, a receptacle having a portion located directly beneath and adjacent to said member so as to receive the articles side by side as they are successively ejected, a plunger having a portion operative in said receptacle to advance the articles therewith, a positively-driven shaft, a crank member thereon, and a rod connecting said crank member and plunger. 115

4. In an assembling machine, the combination of an article-positioning member having intersecting chambers extending therethrough, a positively-driven element, operative connection between said element and member, whereby said member is oscillated to shift its chambers successively to 125 130

1. horizontal and vertical planes, means for delivering articles to the successive chambers of said member when they are in a horizontal plane, a plunger for ejecting the articles from said chambers when they are in a vertical plane, a second positively driven element, operative connection between said latter element and the plunger, a receptacle to which the articles are delivered by said member, a plunger having a portion operative in said receptacle to advance the articles therealong, a third positively-driven element, and operative connection between the same and the latter plunger.
2. In an assembling machine, the combination of an article positioning member, an ejector therefor, means for positively raising said ejector and for permitting it yieldingly to descend, a receptacle into which the articles are delivered, and means for advancing the articles along said receptacle.
3. In an assembling machine, the combination with a member whereby alternate articles delivered thereto are endwise reversed, and means for delivering articles to said member, of a receptacle having a receiving portion located directly below said member and having a portion extending outwardly and upwardly from said receiving portion, and means for progressively advancing the articles deposited in said receiving portion by said member.
4. In an assembling machine, the combination with a member whereby alternate pairs of articles delivered thereto are endwise reversed, and means for delivering successive pairs of articles to said member, of a receptacle having two longitudinal compartments therein, said receptacle having a receiving portion located directly below said member and having a portion extending outwardly and upwardly from said receiving portion, and means for progressively advancing the articles deposited in said receiving portion by said member.
5. In an assembling machine, the combination with an axially mounted member having intersecting passages or chambers extending therethrough, means for oscillating said member, and means for delivering articles to the chambers thereof successively, of a receptacle having a portion located directly beneath and adjacent said member to receive the articles side by side as they are successively discharged from the latter, and means for progressively advancing along said receptacle the articles delivered thereto.
6. In an assembling machine, the combination of an article positioning member comprising a rotary chambered body, means for actuating said body, a receptacle to which the articles are delivered by said

member, a plunger for advancing the articles along said receptacle, and means for actuating said plunger, said plunger including a head having a curved upstanding portion adjacent the said body.

7. In an assembling machine, the combination of an article positioning member comprising a rotary chambered body, means for actuating said body, means for delivering articles to said body, a receptacle to which the articles are delivered by said body, a plunger for advancing the articles along said receptacle, and means for actuating said plunger, said plunger including a head having upstanding side extensions which serve to guide the articles to said body.

8. In an assembling machine, the combination of an article positioning member comprising a rotary chambered body, means for actuating said body, means for delivering articles to said body, a receptacle to which the articles are delivered by said body, a plunger for advancing the articles along said receptacle, and means for actuating said plunger, said plunger including a head having a curved upstanding portion with side extensions which serve to guide the articles to said body.

9. In an assembling machine, the combination of an article positioning member, means for ejecting articles therefrom, a receptacle into which the articles are delivered by said member, a plunger for advancing the articles along said receptacle, and means for actuating said plunger, said latter means including a yielding connection which relieves the force of the plunger on articles which may become clogged between the plunger and the positioning member.

10. In an assembling machine, the combination of a positioning member whereby alternate articles delivered thereto are endwise reversed, means for ejecting articles therefrom, a receptacle into which the articles are delivered by said member, a plunger for advancing the articles along said receptacle, and means for actuating said plunger, said latter means including a sectional rod, spring connection between the sections of the rod, and means for positively reciprocating one of said sections.

11. In an assembling machine, the combination of an article-positioning member having intersecting chambers extending therethrough, means for oscillating said member to shift its chambers successively to horizontal and vertical planes, means for delivering articles to the successive chambers when they are in a horizontal plane, means for ejecting the articles from said chambers successively when they are in a vertical plane, a receptacle having a portion located directly beneath and adjacent to said member so as to receive the articles side by
